Zune user interface, Microsoft Corporation, date unknown but prior to filing.

* cited by examiner

Primary Examiner — Angela J Lee(74) *Attorney, Agent, or Firm* — Banner & Witcoff, Ltd.(57) **CLAIM**

The ornamental design for a display screen with user interface, as shown and described.

DESCRIPTION

The FIGURE is a front view of a display screen with user interface showing my new design.

The broken line showing of the image in the square and the remainder of the display screen is for environmental purposes only and forms no part of the claimed design.
